CLAIM

The ornamental design for a flower table, as shown and described.

DESCRIPTION

FIG. 1 is a front perspective view of the flower table, showing my new design, the broken lines depicting environment and forming no part of the claimed design;

FIG. 2 is a top plan view of the invention illustrated in FIG. 1;
FIG. 3 is a front elevation view of the invention illustrated in FIG. 1;

FIG. 4 is a right side elevation view of the invention illustrated in FIG. 1;

FIG. 5 is a left side elevation view of the invention illustrated in FIG. 1;

FIG. 6 is a rear elevation view of the invention illustrated in FIG. 1; and,

FIG. 7 is a bottom plan view of the invention illustrated in FIG. 1.
